US0D1086947S

(12) **United States Design Patent** (10) Patent No.: **US D1,086,947 S**
(45) Date of Patent: ** Aug. 5, 2025

(54) **MOTORCYCLE OR MOTORCYCLE
REPLICA**

(71) Applicant: **HONDA MOTOR CO., LTD.**, Tokyo
(JP)

(72) Inventors: **Asato Kato**, Wako (JP); **Martin
Pettersson**, Wako (JP)

(73) Assignee: **HONDA MOTOR CO., LTD.**, Tokyo
(JP)

(**) Term: **15 Years**

(21) Appl. No.: **29/925,902**

(22) Filed: **Jan. 26, 2024**

(30) **Foreign Application Priority Data**

Jul. 28, 2023 (JP) ..... 2023-015540 D

(51) **LOC (15) Cl.** **12-11**

(57) **CLAIM**

The ornamental design for a motorcycle or motorcycle replica as shown and described.

DESCRIPTION

FIG. 1 is a front and left perspective view of a motorcycle or motorcycle replica, showing our new design;

FIG. 2 is a rear and left perspective view thereof;

FIG. 3 is a front and right perspective view thereof;

FIG. 4 is a rear and right perspective view thereof;

FIG. 5 is a left side elevation view thereof;

FIG. 6 is a right side elevation view thereof;

FIG. 7 is a front elevation view thereof;

FIG. 8 is a rear elevation view thereof;

FIG. 9 is a top plan view thereof; and,

FIG. 10 is a bottom plan view thereof.

The broken lines shown in the drawings illustrate portions of the motorcycle or motorcycle replica that form no part of the claimed design.

1 Claim, 10 Drawing Sheets
